UNITED STATES PATENT OFFICE.

OSCAR E. McCASKILL, OF FORT WORTH, TEXAS.

INVOLUTING DRAWING INSTRUMENT.

1,106,883.

Specification of Letters Patent. Patented Aug. 11, 1914.

Application filed November 17, 1913. Serial No. 801,358.

To all whom it may concern:

Be it known that I, OSCAR E. McCASKILL, a citizen of the United States, residing at Fort Worth, in the county of Tarrant and State of Texas, have invented certain new and useful Improvements in Involuting Drawing Instruments, of which the following is a specification.

This invention relates to a drawing instrument and particularly to a drawing instrument for drawing involuting curves, and the object is to provide a simple and highly efficient mechanism for using a drawing pen or pencil, or other instrument, and which will be easily operated.

Other objects and advantages will be fully explained in the following description and the invention will be more particularly pointed out in the claims.

Reference is had to the accompanying drawings which form a part of this application.

Figure 1 is a side elevation of the drawing instrument. Fig. 2 is a side elevation of the spacing and adjustment wheel and guide. Fig. 3 is an end view of the pen carrier or chuck. Fig. 3^a is a vertical section of the same. Fig. 3^b is a bottom plan view of the same. Fig. 4 is a horizontal section of the pivot post taken along the line J—J of Fig. 1. Fig. 5 is a detail view of the adjusting screw shaft. Fig. 6 is a side elevation, showing a variation in the pen carrier. Fig. 7 is an end elevation of the same.

Similar characters of reference are used to indicate the same parts throughout the several views.

The drawing instrument includes a wheel A which is provided with a rubber rim or with a rim of some substance which will have some friction. This wheel is for the purpose of spacing the distance between the curves to be made and also for adjusting a screw shaft C. The wheel A may be considered also a tangential guide. The wheel A is made rigid with the shaft C by a set screw B. The screw shaft C is journaled in a pivot post D and turns freely in this post. The screw shaft C has an annular groove K therein and a set screw I is screwed into the pivot post D and projects into the groove K to prevent longitudinal movement of the shaft C through the pivot post D. A guide rod E is fixedly mounted in the pivot post D and held therein by a pin L. The carrier F for the drawing instrument has apertures M for

the guide E and N for the screw shaft C. The carrier F will move freely on the guide rod E.

When the instrument is in operation the wheel A is moved around on the paper or cloth or other material on which the drawing is being made and as the wheel A moves it turns the shaft C and as the shaft C turns the carrier F will be moved in the direction of the threads on the shaft C. It will be noted that the threads on the shaft C may be either right or left threads.

A pen H is provided and enters a socket F'' in the lower part of the carrier F. The pen H is held in place by a spring G which has one end rigid in the carrier F and the other end projecting into the upper part of the pen H. This provision allows a yielding motion to the pen and will always insure contact of the pen on the paper or cloth or other material on which the curves are to be drawn. The pen H is provided with a set screw O for opening or closing the two parts of the pen for the purpose of drawing narrower or wider lines.

A variation of the pen holder or carrier is shown in Figs. 6 and 7. The pen H is provided with a shank P and a socket V is formed on one edge of the carrier F'. The shank P will move freely through the socket V and is connected to a holder T above the carrier F'. The shank P is made rigid with the bar T and a spiral spring R is mounted on the shank P between the carrier F' and the pen H. The shank P can thus move freely through the socket V, but is held yieldingly downward by a spiral spring R. The bar T is guided in its vertical movement by a pin S which is rigid with the carrier F'. The pin S serves as one guide and the socket V serves as another guide for the vertical movement of the pen H.

The function of the rod E is to prevent the turning of the carrier F during a writing or drawing operation and also, as above described, to guide the pen H and to prevent wobbling motion of the same in its radial movement.

It will be observed that by reason of a right thread on the shaft C the pen H may be set near the pivot post D to commence a curve, and as the instrument is operated by turning the wheel A about the pivot post D the curve will become uniformly larger as the wheel A is turned because the thread on the shaft C is uniform and each

complete revolution of the wheel A will continually space the pen H from the pivot post D to cause a larger curve. It will be noted that the wheel A is adjustable on the 5 shaft C and may be set at any point indicated, by the numerals 2 to 10, inclusive. When the wheel A is set close to the pivot post D, the curved line being made will run close to the previous curve, but when the 10 wheel A is set farther from the post D, the space between the curves will become wider. The farther the wheel A is away from the pivot post D, the more times the shaft C will turn on one rotation about the pivot 15 point and thus move the chuck or carrier F the faster away from the pivot point.

What I claim, is:—

1. A drawing instrument comprising a pivot post, a screw shaft journaled in said post, means for preventing longitudinal movement of said shaft through said post, a guide and spacing wheel rigid with said shaft, a carrier mounted on said shaft and provided with a threaded opening there- 20 through for said shaft, said shaft having threads engaging the threads in said carrier, a guide rigid with said post and extended through said carrier, and a pen carried by said carrier.
2. A drawing instrument having a pivot post, a shaft journaled in said post and having screw threads on one end, a wheel rigid with the other end of said shaft for turning said shaft, a carrier mounted on the thread- 25 ed portion of said shaft and carrying a pen

yieldingly mounted therein and a guide for said carrier rigid with said pivot post.

3. A drawing instrument having a pivot post, a shaft journaled in said post and provided with screw threads on one end, a 40 wheel rigid with the other end of said shaft, said shaft having an annular groove therein, a screw in said pivot post projecting into said groove, a carrier mounted on the threaded portion of said shaft and provided with an opening through the upper part 45 thereof, a guide for said carrier rigid with said pivot post and projecting through said opening, and a drawing pen yieldingly mounted on the said carrier.

4. A drawing instrument having a pivot post provided with a bearing, a screw shaft journaled in said bearing and provided with threads on one end, an adjusting wheel rigid with the other end of said shaft, a car- 50 rier carried on the threaded portion of said shaft and having an aperture through the upper part thereof, a guide moving freely 55 through said aperture and rigid with said pivot post, a pen mounted in said carrier, and means provided for a yielding vertical motion of said pen.

In testimony whereof, I set my hand in the presence of two witnesses, this 16th day of October, 1913.

OSCAR E. McCASKILL.
